(57) **CLAIM**

We claim the ornamental design for a housing element for a regenerative blower, as shown and described.

DESCRIPTION

FIG. 1 is a top right front perspective view of the housing element for a regenerative blower.

FIG. 2 is a top right rear perspective view of the housing element for a regenerative blower.

FIG. 3 is a top left rear perspective view of the housing element for a regenerative blower.

FIG. 4 is a top left front perspective view of the housing element for a regenerative blower.

FIG. 5 is a bottom right front perspective view of the housing element for a regenerative blower.

FIG. 6 is a bottom right rear perspective view of the housing element for a regenerative blower.

FIG. 7 is a bottom left rear perspective view of the housing element for a regenerative blower.

FIG. 8 is a bottom left front perspective view of the housing element for a regenerative blower.

FIG. 9 is a front view of the housing element for a regenerative blower.

FIG. 10 is a rear front of the housing element for a regenerative blower.

FIG. 11 is a right side view of the housing element for a regenerative blower.

FIG. 12 is a left side view of the housing element for a regenerative blower; and,

FIG. 13 is top view of the housing element for a regenerative blower.

The broken lines represent boundaries of the claimed design, and the broken lines and unshaded surfaces within them form no part of the claimed design.

1 Claim, 13 Drawing Sheets
